(57) **CLAIM**

The ornamental design for a gate operator housing, as shown and described.

DESCRIPTION

FIG. 1 is a perspective view of a gate operator housing showing our new design;

FIG. 2 is a top plan view thereof;

FIG. 3 is a right-side view thereof;

FIG. 4 is a front view thereof;

FIG. 5 is a bottom plan view thereof;

FIG. 6 is a left-side view thereof; and,

FIG. 7 is a rear view thereof.

The broken lines shown represent unclaimed subject matter and form no part of the claimed design.
